DOOR HOLDING AND DOOR CONTROL
MECHANISM

Rudolph I. Schonitzer, Shaker Heights, Ohio

Application September 14, 1938, Serial No. 229,800

14 Claims. (Cl. 292—216)

This invention relates to door holding and door control mechanism, whereby a hinged door, such as an automobile door, for example, may be more or less rigidly or unyieldably held against movement in the general direction of its hinge axis when in closed position within its surrounding frame and whereby said door may be suitably controlled, the door control being a latch control or a throw-out control or a combined latch and throw-out control, all as will hereinafter more fully appear.

In my prior United States patent for a Door support, Patent No. 1,963,475, two separate and independent means are disclosed for rigidly holding a hinged door, such as an automobile door, against movement in the general direction of its hinge axis when such door is in closed position within its surrounding frame, but neither of such door holding means is combined or cooperatively related with any control means for said door, including the lock or latch control means therefor. In my prior United States patent for Door control mechanism, Patent No. 2,094,413, mechanism is disclosed for suitably controlling a hinged door, such as an automobile door, for example, the door control there disclosed being a latch control or a throw-out control or a combined latch and throw-out control. However, in that patent, the door control mechanism is not combined or cooperatively related with any holding means for said door.

The present invention, therefore, has for its general object the provision of mechanism which comprises combined or cooperatively related door holding parts and door controlling parts, the combination or cooperative relation of such parts being of such character that the more or less rigid or unyieldable holding of a door against movement in the general direction of its hinge axis when such door is in closed position and the control of such door are effected in a particularly novel and exceedingly practical manner.

A further object of the present invention is the provision of door holding and door control mechanism for a hinged automobile door or the like, the use of said mechanism obviating the necessity of providing for such door "dove-tails" or other separate devices such as are now utilized for door holding purposes.

A further object of the present invention is the provision of door holding and door control mechanism for a hinged automobile door or the like, said mechanism being of such character that the door with which it is used has a single predetermined closed position, irrespective of the presence

or absence of the yieldable door bumpers which are now provided for automobile doors. With such mechanism, therefore, the use of such door bumpers is entirely optional.

A further object of the present invention is the provision of door holding and door control mechanism which is of extremely simple and inexpensive construction; which comprises readily and conveniently assembled parts of strong and sturdy character; which provides for the necessary initial adjustment of parts to enable said mechanism to be used with any door, notwithstanding normal variations in the mounting thereof, etc.; and which mechanism does not require any attention during its exceptionally long life, as wear of the parts is automatically taken care of.

Further objects of the present invention are in part obvious and in part will appear from the following description of several embodiments thereof, reference being had to the accompanying drawings in which such embodiments are illustrated in connection with a hinged automobile door, said door and its surrounding frame being of standard form.

In said drawings, in which Figs. 1 to 6 inclusive illustrate one form of mechanism embodying the present invention, Fig. 1 is an elevation of a side portion of an automobile body door frame to which are secured certain parts of such mechanism; Fig. 2 is an elevation of a portion of a side edge wall of a hinged automobile door to which are secured other parts of such mechanism; Fig. 3 is a vertical longitudinal sectional view, on the line 2—3, Fig. 4, through such portions of said automobile body door frame and said automobile door, the door being latched in closed position and being rigidly or unyieldably held against up and down movement within its frame; Fig. 4 is a vertical cross-sectional view of such portions, on the line 4—4, Fig. 3; Fig. 5 is a vertical cross-sectional view through a portion of the automobile door, the parts of the mechanism there shown being in the positions which they occupy when the door is in its closed position; Fig. 6 is a view similar to Fig. 5, but showing such parts in the positions which they occupy when the door is open; Figs. 7 and 8 are views illustrating another form of mechanism embodying the present invention, Fig. 7 being a view on the line 7—7, Fig. 8, and corresponding in part to Fig. 3, and Fig. 8 being a view on the line 8—8, Fig. 7, and corresponding in part to Fig. 4; Figs. 9 and 10 are views illustrating another form of mechanism embodying the present invention, Fig. 9 being a view corre-

sponding in part to Figs. 4 and 8, and Fig. 10 being a view similar to Fig. 9, with the pivoted door control member shown by dot-dash lines in operated position; Figs. 11 and 12 are views corresponding respectively to Figs. 9 and 10 and showing another form of mechanism embodying the present invention; and Figs. 13 and 14 are views corresponding respectively to Figs. 9 and 10 and showing another form of mechanism embodying 10 the present invention.

Before the present invention is described in detail, it is to be understood that such invention is not limited to the details of construction and/or the specific arrangements of parts herein illustrated and/or described, as the invention obviously may take other forms. It also is to be understood that the phraseology or terminology herein employed is for the purpose of description and not of limitation, there being no intention and 20 no desire to limit the present invention, as herein disclosed and as defined in the appended claims, beyond the requirements of the prior art.

Although door holding and door control mechanisms embodying the present invention are applicable for use with the hinged doors of various structures, such as with the doors of refrigerators and with the doors of various kinds of buildings, for example, such mechanisms are particularly adapted for use with the hinged doors of present-day automobiles. In such automobile doors, window panes are slidably mounted and for greater visibility, such panes are movable into close proximity with certain sections of the free side edge walls of said doors, as fully disclosed in 30 my aforesaid Patent No. 2,094,413 for Door control mechanism. Like the door control mechanisms illustrated in such patent, the door holding and door control mechanisms here illustrated are of such character that they may be readily and 40 conveniently associated with such door sections, without interfering in any way with the movement of the window panes within said doors.

As heretofore pointed out, the door control provided by the present invention may be (A) a latch control only, or (B) a throw-out control only, or (C) a combined latch and throw-out control. Solely for purposes of illustration, the accompanying drawings show embodiments of the present invention which provide combined latch and throw-out controls, but if desired, the mechanisms constituting such embodiments may be 50 readily modified, in an exceedingly simple and inexpensive manner, to provide latch controls only or throw-out controls only, as will be hereinafter explained.

Although the door control parts (and, of course, the door holding parts) of mechanisms embodying the present invention may vary or differ widely as to construction, arrangement, actuation, etc., 60 the door control parts here shown are, generally speaking, of the same character as those disclosed in my aforesaid Patent No. 2,094,413 for Door control mechanism, to which patent reference may be had. For simplicity and convenience, 65 only those door control parts which are necessary or desirable for a proper understanding of the present invention are here illustrated.

Referring now to that embodiment of door holding and door control mechanism illustrated 70 in Figs. 1 to 6 inclusive, it will be noted that the door control parts of such mechanism (latch and throw-out control parts) include a door latch arm 12 and a door throw-out arm 13, said arms being either separate members, or as here shown, 75 integral parts of a generally flat bifurcated mem-

ber 14 of metal or other rigid material. For cooperation with said arms in the latch and throw-out control of the hinged automobile door 16 (which door is a standard metal door such as is now used in the automotive industry), any suitable means may be utilized, the means here shown being a simple keeper pin 17 of metal or other rigid material.

As pointed out in my aforesaid Patent No. 2,094,413 for Door control mechanism and as will 10 be readily understood, either the arms 12 and 13 (the bifurcated door control member 14) or the keeper pin 17 may be associated with the automobile door 16 and the other associated with the automobile body door frame therefor. As 15 here shown (the embodiment of Figs. 1 to 6 inclusive), the arms 12 and 13 are associated with a section 18 of the free side edge wall (the edge wall opposite the hinged edge wall) of the door 16, and the keeper pin 17 is associated with a 20 section 19 of the automobile body door frame, as in my aforesaid Patent No. 2,094,413 for Door control mechanism, said door section 18 and said door frame section 19 being adjacent and in suitable alignment when the door 16 is in closed 25 position, as indicated in Fig. 3.

The association of the latch and throw-out arms 12 and 13 with the wall section 18 of the "latch" side of the automobile door 16 is here effected by the use of a relatively short stub shaft 30 21 which extends generally horizontally through such wall section and has oscillatory movement about its general horizontal longitudinal axis. On that end portion of said stub shaft which here lies outside the door 16 is rigidly mounted the bifurcated door control member 14 of which the arms 12 and 13 are parts, the securement of said bifurcated member on said stub shaft being such that the arms 12 and 13 are here dependently disposed relative thereto, as clearly shown in the accompanying drawings. Any suitable support for the stub shaft 21 may be utilized, and in the embodiment of the invention illustrated in Figs. 1 to 6 inclusive, an intermediate portion of said stub shaft is suitably supported, for oscillatory movement, in the transverse portion 22 of what is here termed a latch plate, said latch plate being here arranged within the door 16 and such transverse portion of said latch plate being located alongside, and rigidly secured to, said door wall section 18.

Rigidly mounted on the other end portion of the stub shaft 21, within the automobile door 16, is a generally flat plate-like element 24 of metal or any other suitable material, said element lying alongside the transverse portion 22 of the latch plate and hence being closely adjacent the door wall section 18. Inasmuch as both said element and the bifurcated door control member 14 are here rigidly mounted on the stub shaft 21, oscillatory movement of the latch and throw-out arms of said bifurcated member effects corresponding movement of said element and oscillatory movement of said element effects corresponding movement of said latch and throw-out arms, the movement of said arms and said element, in this embodiment of the present invention, being in planes substantially vertical and transversely of the side walls of said door.

As heretofore pointed out, the keeper pin 17 is associated with the side edge wall section 18 of the automobile body door frame for the door 16, the disposition of the longitudinal axis of said keeper pin being substantially horizontal. The association of said keeper pin with said door

frame wall section 19 is here of such character that said keeper pin is immovable in an up and down direction relative to such door frame wall section 19 when the door 16 is closed. As here shown, such an association is effected by providing said keeper pin with a rigid base plate 26 which is rigidly secured, such as by screws 27 or the like, to an anchor plate 28 lying behind said wall section 19, with the result that said keeper pin base plate and said-anchor plate are rigidly or immovably secured or clamped on opposite sides of said wall section. To permit, prior to such rigid securing thereof, limited adjustment of said keeper pin 17, either horizontally or vertically, for the compensation of variations, etc., in the manufacture and/or in the mounting of the door 16, the openings 29 in said door frame wall section 19 for the shanks of the screws 27 are made somewhat larger than said screw shanks, as clearly shown in Fig. 3. For the convenient holding of the anchor plate 28, to facilitate assembly of the parts, etc., a suitable retainer 30 is here welded or otherwise suitably secured to the inner surface of the door frame wall section 19, the chamber of said retainer being of somewhat greater area than that of said anchor plate to permit said anchor plate to be positioned therein in accordance with the positioning of the keeper pin base plate 28.

As will hereinafter more fully appear, the latch and throw-out arms 12 and 13 are movable between a single predetermined operative position, shown in Figs. 3, 4 and 5 and in full lines, Fig. 2, and a predetermined operated position, shown in dotted lines, Figs. 2 and 6. The single predetermined operative position of the latch arm 12 is its door-latching position, (see Fig. 4, for example), in which position such arm extends downwardly along the inner side of the keeper pin 17 and effectively and positively latches the automobile door 16 in a single predetermined closed position. The predetermined operated position of the latch arm 12 is its unlatching position, (see Fig. 6, for example), in which position said arm extends inwardly and downwardly, with no door-latching effect upon the keeper pin 17. The single predetermined operative position of the throw-out arm 13 is what may be termed its potential door throw-out position, a position in which said arm extends downwardly along the outer side of the keeper pin 17 (see Fig. 4, for example), ready for door-throw-out or door-opening movement. The predetermined operated position of said throw-out arm is what may be termed its door thrown-out position, the door having been thrown out by said arm to at least partially open position and said arm being inwardly and downwardly disposed, as clearly shown in dotted lines, Figs. 2 and 6.

In mechanism embodying the present invention, whether the door control provided thereby is a latch control only or a throw-out control only or a combined latch and throw-out control, means is provided for automatically maintaining the door control arm or arms in operated position whenever the door with which such mechanism is used is open. If the mechanism is to provide a door latch control only, such maintaining means may be of any suitable nature. If the mechanism is to provide a door throw-out control only or a combined door latch and door throw-out control, such maintaining means is preferably a power means of one kind or another. With mechanism providing a door

throw-out control only, such power means may also be used to move the throw-out arm from its predetermined operative position to its predetermined operated position, to effect automatic throw-out or opening movement of the door with which such mechanism is used; and with mechanism providing a combined door latch and door throw-out control, such as is here illustrated, such power means also may be utilized to move the latch arm from its predetermined operative position to its predetermined operated position, to effect unlatching of the door with which such mechanism is used and to move the throw-out arm from its predetermined operative position to its predetermined operated position, to thereby effect automatic throw-out or opening movement of such door.

In the embodiment of the present invention as illustrated in Figs. 1 to 6 inclusive, a generally flat spiral spring 32 (see Figs. 5 and 6) is utilized not only as the means for automatically maintaining the latch and throw-out arms in their predetermined operated position when the automobile door 16 is open but also, as a means for automatically moving said latch and throw-out arms from their single predetermined operative position to such predetermined operated position, whenever unlatching of the door and opening or throw-out movement thereof are desired. For the accomplishment of those two functions, the springs 32, which is here suitably mounted on the transverse portion 22 of the latch plate, contacts with or is effective upon the element 24 of the shaft 21, with the result that the latch and throw-out arms 12 and 13 of said shaft are normally urged by said spring toward their predetermined operated position.

As will be readily understood, the operated position of the latch and throw-out arms 12 and 13 is controlled by the extent of the inward swinging movement (clockwise movement, Figs. 5 and 6) of such arms, which in turn is controlled by the extent of inward movement (clockwise movement, Figs. 5 and 6) of the shaft element 24 with which such arms turn. To yieldingly but effectively limit inward or clockwise movement of the shaft element 24, when the latch and throw-out arms have been swung inwardly or clockwise to the desired and predetermined extent, a suitable yieldable abutment is here provided for such shaft element. As here shown, said yieldable abutment is a metal-capped rubber block 34 which is suitably secured to a longitudinally disposed portion 35 of the latch plate, said latch plate portion 35 preferably lying alongside or adjacent the inner side wall 36 of the automobile door 16, as shown in Figs. 5 and 6.

When the automobile door 16 is open, the latch and throw-out arms 12 and 13 are in their operated position (their dotted line position, Fig. 6), said arms having been moved to, and being maintained in, such operated position by the spring or power means 32. During the latter part of the closing movement of said automobile door, the throw-out arm 13 strikes the keeper pin 17 on the automobile body door frame, and with said throw-out arm acting somewhat as a crank arm, the final movement of the door 16 to closed position enables said keeper pin and said "crank acting" throw-out arm to bring about the movement of the latch and throw-out arms to their single predetermined operative position (their dotted line position, Fig. 5), on opposite sides of said keeper pin, (see Fig. 4), the latch arm being then in its door-latching position and the throw-

out arm being then in what has heretofore been termed its door throw-out position, that is, in position to throw the door outwardly to at least partially open position upon the unlatching thereof.

In order to enable the latch and throw-out arms 12 and 13 to be releasably detained in their single predetermined operative position, upon opposite sides of the keeper pin 17, upon the closing of the door 16, notwithstanding the normal tendency of the power spring 32 to move said arms toward their operated position, mechanism embodying the present invention includes suitable detent means for such purpose. In the embodiment of the invention illustrated in Figs. 1 to 6 inclusive, the detent means is a generally flat plate-like member 40 of metal or other suitable material, said detent member being pivotally mounted by the use of a suitable pin 41 on the transverse portion 22 of the latch plate and being located just above the shaft element 24 with which said detent member cooperates in the releasable detention of the latch and throw-out arms in their single predetermined operative position when the door 16 is in closed position.

Although the detent member 40 and the shaft element 24 may be provided with cooperating abutments of any suitable form and location, for the releasable detention of the latch and throw-out arms in their single predetermined operative position when the automobile door is in closed position, such detent member and such shaft element are here provided with cooperating edge abutments or shoulders 44 and 45, respectively.

As will be readily understood, any suitable means may be utilized to effect detaining cooperation or engagement of such shoulders 44 and 45 upon the movement of the latch and throw-out arms to their single predetermined operative position.

For example, the weight of the detent member 40 may be so distributed that said member has a normal gravitational tendency to turn in a counter-clockwise direction (Figs. 5 and 6) to effect detaining cooperation or engagement of its shoulder 44 with the shaft element shoulder 45 upon the closing of the door 16 or, if desired, spring means may be utilized, either with or without gravitational aid, to bring about such a tendency on the part of the detent member 40 to move in such a counter-clockwise direction. To insure detaining cooperation or engagement of the shoulders 44 and 45 of the detent member 40 and the shaft element 24, whenever the latch and throw-out arms 12 and 13 are moved to their predetermined operative position, not only is the weight of said detent member so distributed that said member has a normal gravitational tendency to turn in a counter-clockwise direction (Figs. 5 and 6) but also, suitable spring means 48 is utilized to cause said detent member to normally tend to turn in such counter-clockwise direction.

As here shown, the spring means 48 is a simple wire spring having its intermediate portion coiled about the pivot pin 41 for the detent member 40 and having its end portions anchored to or otherwise suitably associated with said detent member and the transverse portion 22 of the latch plate.

In the use of mechanisms embodying the present invention with the doors of certain structures, such as with the doors of refrigerators, for example, it will probably be sufficient to provide such mechanism with a single manually operable means for the actuation of the detent means of such mechanism to effect the release of the door

control arm or arms thereof. In the use of mechanism embodying the present invention with the door of an automobile, however, two manually operable means for such releasing actuation of the detent means preferably should be provided, namely, an outside manually operable means and an inside manually operable means, so that either a person outside or a person inside said automobile can conveniently effect the unlatching of the automobile door with which such mechanism is used, or the outward throwing of such door to at least partially open position, or both. Although the accompanying drawings show door holding and door control mechanisms as used with an automobile door, the particular character of the means, or the number of such means, for effecting releasing actuation of the detent member 40 form no part of the present invention, and in the accompanying drawings, therefore, a single outside means is illustrated for effecting such actuation of the detent member 40. In my prior Patent No. 2,094,413 for Door control mechanism, however, two manually operable means (one an outside means and the other an inside means) are disclosed for selectively effecting releasing actuation of a detent member of the character of the one here illustrated, and reference to that patent may be had, if desired, for a disclosure of an inside manually operable means for effecting such actuation of the detent member 40 here shown.

The single outside means here illustrated for effecting releasing actuation of said detent member 40 is a simple push button 50 suitably mounted, adjacent said detent member, in the outer side wall 51 of the automobile door 16, said push button being adapted, when manually depressed, to have direct operative engagement with said detent member for the actuation thereof. Inasmuch as said push button engages or contacts with said detent member below the pin 41, about which said detent member pivots or swings, manual depression of said push button directly effects clockwise movement (Figs. 5 and 6) of said detent member, with the consequent release of the shaft element 24 and the consequent movement of the latch and throw-out arms 12 and 13 to their predetermined operated position, all as will be readily understood.

The general operation of the door control parts of the present door holding and door control mechanism, as exemplified by the embodiment of the invention illustrated in Figs. 1 to 6 inclusive, is as follows:

When the door 16 is in closed position, the latch and throw-out arms 12 and 13 are in their single predetermined operative position on opposite sides of the keeper pin 17 (as in Fig. 4), the latch arm 12 being in latching position, with the consequent latching of the door in its single predetermined closed position, and the throw-out arm 13 being in throw-out position, that is, in position to effect the automatic throwing of such door to at least partially open position upon the unlatching thereof. The releasable detention in their single predetermined operative position of the latch and throw-out arms, when the door 16 is in closed position, is effected by the detent member 40, the shoulder 44 of which has releasable detaining cooperation or engagement at such times with the shoulder 45 of the shaft element 24. As the detent member 40 has a normal tendency to move in a counter-clockwise direction, Figs. 5 and 6, under the influence of gravity and its spring 48, and as the shaft element 24 has a

normal tendency to move in a clockwise direction, Figs. 5 and 6, under the influence of the relatively powerful spring 32, releasable detaining cooperation or engagement of the shoulders 44 and 45 is effectively maintained when the door is in closed position, so that there is no liability of the accidental unlatching of the door, due to road shocks or the like.

When it is desired to unlatch said door and 10 automatically effect the throwing of said door to at least partially open position, releasing actuation (clockwise movement, Figs. 5 and 6) of the detent member 40 is manually effected, such as by manual depression of the push button 50 in 15 the embodiment of the invention illustrated in Figs. 1 to 6 inclusive. Upon completion of such releasing actuation (clockwise movement, Figs. 5 and 6) of the detent member 40, in unison clockwise movement of the shaft element 24, the shaft 21, 20 and the arms 12 and 13 automatically results, said arms moving from their single predetermined operative position, Fig. 5, to their predetermined operated position, Fig. 6. As the operated position of said latch arm is its unlatching position, 25 the movement of said latch arm to such operated or unlatching position effects, of course, the unlatching of the door 16, and as the operated position of said throw-out arm is its door thrown-out position, the movement of such throw-out 30 arm to its operated or thrown-out position effects, of course, the throwing of said door to at least partially open position. Due in large part to the character of the cooperating shoulders 44 and 45 of the detent member 40 and the shaft element 35 24 (said shoulders 44 and 45 preferably being either the chord or the arc of a circle of which the detent member pivot pin 41 is the center) (see, for example, Fig. 26 of the drawings, and the latter part of the first column of page 6 of the 40 specification of my aforesaid Patent No. 2,094,413 for Door control mechanism), clockwise releasing actuation of the detent member 40 is easily effected, the amount of pressure required for the depression of the push button 50 being extremely 45 small.

When the automobile door 16 is open, the latch and throw-out arms 12 and 13 are in their operated position, as shown in dotted lines, Figs. 2 and 6, the operated position of the latch arm 50 being its unlatching position and the operated position of the throw-out arm being its door thrown-out position. As heretofore pointed out, upon the closing of said door, the door throw-out arm 13 strikes the keeper pin 17 on the automobile body door frame, and continued closing movement of said door results in the movement of said latch and throw-out arms to their single predetermined operative position, on opposite sides of said keeper pin, the throw-out arm in 55 such cooperation with said keeper pin acting as a "crank arm", as will be readily understood. Upon the closing of the door, therefore, the latch arm 12 is moved to its single predetermined operative or latching position, with the consequent latching of the door in a single predetermined closed position, and the throw-out arm 13 is moved to its single predetermined operative or door throw-out position, ready for automatic door throw-out movement when the door is next unlatched. In 60asmuch as the shaft element 24 moves in unison with the latch and throw-out arms, the closing of the door 16 also moves said shaft element into cooperative relationship with the detent member 40, the shoulders 44 and 45 of said detent member and said shaft element being thus brought

into releasable detaining cooperation or engagement. Upon the closing of the door 16, therefore, the detent member 40 becomes effective to releasably detain, when the door is in closed position, the latch and throw-out arms in their single 5 predetermined operative position. As will also be understood, the closing of the door 16 also results in the "loading" of the power spring 32, inasmuch as the upper end portion of said spring is moved to "loaded" position by the shaft element 24 upon the closing of said door.

As clearly shown in the accompanying drawings (see Figs. 2 and 4), the throw-out arm 13 preferably has a suitable cam 54 on the inner edge of its free end portion, not only for cooperative engagement with the keeper pin 17 in the movement of the latch and throw-out arms 12 and 13 to their operative position upon the closing of the door 16 but also, for cooperation with such keeper pin in the throwing of such door to 20 at least partially open position upon the unlatching of said door. As will also be noted from an examination of the accompanying drawings, the free end of the throw-out arm 13 is disposed beyond the free end portion of the latch arm 12, 25 or in other words, the distance between the free end of the throw-out arm and the longitudinal axis of the shaft 21, about which the latch and throw-out arms swing or pivot, is somewhat greater than the distance between the free end 30 of the latch arm 12 and such shaft axis. One of the advantages of such a construction is that the movement of the latch and throw-out arms to their single predetermined operative position, and the consequent latching of the door 16 in 35 its single predetermined closed position, can be more easily and more efficiently effected, and another of the advantages thereof is that the outward throwing movement of such door can be more easily and more efficiently effected, with 40 the door being thrown open to a somewhat greater extent, say to six inches or so. As to such first-mentioned advantage, it may be pointed out (a) that the inward swinging movement (clockwise movement, Figs. 2 and 6) of the latch 45 and throw-out arms need not be of such extent as to horizontally dispose said arms for an operated position thereof, the present latch and throw-out arms when in their predetermined operated position (their dotted line position, Figs. 50 2 and 6) being angularly disposed, and (b) that the latch arm 12, in moving from its predetermined operated position to its single predetermined operative position, clears the keeper pin 17 and does not actually engage such pin until 55 such arm is in substantially its operative position.

As heretofore pointed out, mechanism embodying the present invention not only effects the control of a hinged door, such as the latch and throw-out control of the automobile door 16, as just described, but also effects, when said door is in closed position, the more or less rigid or unyieldable holding of the "latch" side* of such door against movement in the general direction 65 of its hinge axis (in an up and down direction in the case of the automobile door 16 here shown).

As clearly shown in Figs. 3 and 4 of the accompanying drawings in connection with the embodiment of the invention illustrated in Figs. 1 70 to 6 inclusive, the bifurcated door control member 14 rests or seats upon the rigid keeper pin 17 when the automobile door 16 is in closed position, said keeper pin being located at such times at the inner and upper end of the slot or recess 75

68 of said bifurcated member. Inasmuch as said keeper pin is here rigidly mounted on the automobile body door frame, and hence is immovable in an up and down direction relative to such 5 automobile body door frame, and inasmuch as the rigid bifurcated door control member 14 is immovable in an up and down direction relative to the automobile door 16 when such door is in closed position, the seating engagement of said 10 bifurcated door control member on said keeper pin effects the rigid or unyieldable holding of the "latch" side of said door against downward movement when said door is in its closed position, as will be readily understood.

15 For rigidly holding the "latch" side of the automobile door 16 against upward movement relative to the surrounding frame therefor when said door is in its closed position, the door holding and door control mechanism of Figs. 1 to 6 20 inclusive includes a horizontally disposed take-up member or wedge 60 and a suitable retainer therefor, said take-up member or wedge, as here shown, being of metal or other rigid material and being slidably mounted within its retainer for 25 door-holding cooperation with the bifurcated door control member 14. In this particular embodiment of the invention, the take-up member or wedge 60 and its retainer are transversely associated with the wall section 15 of the automobile body door frame for the door 16, said 30 take-up member or wedge being located a sufficient distance above keeper pin 17 on said wall section to permit the bifurcated door control member 14, associated with the door 16, to be 35 rigidly wedged therebetween for door-holding purposes when said door is in its closed position.

As here shown, the retainer for the take-up member or wedge 60 comprises two rigid retainer plates 61 and 62, upper and overlapping portions 40 of which are rigidly secured, such as by the screw 63, to the anchor plate 28 heretofore referred to and which is located behind the wall section 19 of the automobile body door frame. Overlapping and angularly disposed intermediate portions 45 64 and 65 of said retainer plates provide at all times a rigid or unyieldable upper abutment for the take-up member or wedge 60, said take-up member or wedge being arranged for endwise slidable movement in the chamber 50 formed by the spaced lower end portions 67 and 68 of said retainer plates. For the purpose of enabling said take-up member or wedge to be retained within such chamber, a longitudinally disposed and transversely extending groove 70 is 55 here provided in a side wall of said take-up member or wedge, and into such groove extends a correspondingly disposed transverse edge flange 71 of the retainer plate portion 67. To limit the slidable movement of the take-up member or 60 wedge 60 within the chamber of its retainer, the movement of said take-up member or wedge being transversely of the longitudinal axis of the stub shaft 21 on which is rigidly mounted the bifurcated door control member 14 and the shaft 65 element 24, the ends of said chamber are here closed by portions 73 and 74 of one of said retainer plates, and to normally urge said take-up member or wedge outwardly for wedging cooperation with the bifurcated door control member 14 when the door 16 is closed, a helical compression spring 76 is here interposed between 70 said take-up member or wedge and the end wall 14 of the retainer chamber therefor. If desired and as here shown, the inner end portion of said 75 take-up member or wedge may be provided with

a suitable socket 78 for the reception of the outer end portion of the helical compression spring 76 and the chamber end wall 74 may be provided with a centering projection 79 for the inner end of said spring, the effect of said socket and said centering projection being to maintain the spring 76 in horizontal alignment at all times with the longitudinal axis of the take-up member or wedge 60, as will be readily understood.

Upon the closing of the automobile door 16, 10 the bifurcated door control member 14 associated with said door moves beneath the take-up member or wedge 60, the top surface 81 of said bifurcated member and the bottom surface 82 of said take-up member or wedge being thus 15 brought into cooperative door holding engagement. As here shown, the bottom contact surface 82 of said take-up member or wedge is downwardly and inwardly inclined from its outer end, and the top contact surface 81 of the bifurcated door control member 14, when such surface is in cooperative engagement with the bottom surface 82 of said take-up member or wedge, has a corresponding inclination, the effect of which is to insure proper cooperative engagement of said contact surfaces upon the movement of the door 16 to closed position. As clearly shown in Fig. 4, however, the angle of inclination of the contact surfaces 81 and 82, when said surfaces are in cooperative engagement, is only about twelve degrees to the horizontal, or in other words, to the generally horizontal path of movement of the take-up member or wedge 60, so that the inclination of such contact surfaces is what may be termed a "locking" 25 inclination and hence is one that does not prevent cooperative engagement thereof from effecting the desired rigid holding of the "latch" side of the door 16 against upward movement when said door is in its closed position. 30

Because of the normal tendency of the take-up member or wedge 60 to move outwardly, under the influence of its compression spring 76, the rigid bifurcated door control member 14 is rigidly or unyieldably positioned and wedged, 45 upon the movement of the door 16 to closed position, between the rigid keeper pin 17 and the rigid take-up member or wedge 60, and inasmuch as said keeper pin and said take-up member or wedge are immovable in an up and down 50 direction (the general direction of the hinge axis of the door 16) relative to the automobile body door frame with which they are here associated, the "latch" side of the automobile door 16 is, as a consequence, rigidly or unyieldably 55 held against up and down movement when in its closed position within said body door frame.

As will be readily understood, the compression spring 76 for the take-up member or wedge 60 also performs the function of effectively taking up any variation caused by wear, misalignment, etc., the range of slidable movement of said take-up member or wedge within the chamber of its retainer being sufficiently great for such purpose. As a result, when mechanism 60 embodying the present invention is once installed, no further attention to it is necessary.

In the door holding and door control mechanism constituting the embodiment of the present invention illustrated in Figs. 7 and 8, a modified form of rigid take-up member is utilized for door-holding cooperation with the bifurcated door control member of such mechanism. As shown, the take-up member 85 of the mechanism of Figs. 7 and 8 is a pivotally, rather than 75

slidably, mounted part, and for the pivotal mounting of said take-up member, the rigid base plate 26a of the rigid keeper pin 17a is here provided, above said keeper pin, with a rigid pin 86 on which said take-up member pivots, said take-up member being dependently disposed relative to its pivot pin. Like the slideable take-up member or wedge 60 of the mechanism of Figs. 1 to 6 inclusive, the pivoted take-up member 85 of the mechanism of Figs. 7 and 8 is provided with suitable means, such as a spring 88, for normally urging it outwardly. Moreover, the take-up member 85 has its weight so distributed relative to its pivot pin 86 that such member has a normal gravitational tendency to swing outwardly, as will be readily apparent from an examination of Fig. 8. As here shown, the spring 88 is a simple wire spring, the intermediate portion of which is coiled about the pivot pin 86 for the take-up member 85 and the end portions of said spring are suitably anchored to said take-up member and to the keeper pin base plate 26a. For limiting the outward swinging movement of the take-up member 85, under the influence of its spring 88, a stop pin 89 is here secured to the keeper pin base plate 26a, as shown in Fig. 8.

As indicated in Fig. 7 and as will be readily understood, the distance between the top surface of the keeper pin 17a and the convex or cam-shaped bottom surface 90 of the pivoted take-up member 85 is such as to enable the rigid bifurcated door control member 14a to be wedged between said keeper pin and said take-up member upon the movement of the hinged door 16a to its single predetermined closed position, said bifurcated door control member being seated at such times upon said keeper pin and said pivoted take-up member being immovable in an up and down direction relative to the door frame on which it is pivoted when the door 16a is in its closed position. As a result, the "latch" side of the hinged door 16a, like that of the door 16, is rigidly or unyieldably held against up and down movement whenever it is in closed position, all as will be readily understood.

As clearly shown in Fig. 4, the bifurcated door control member 14 of the mechanism illustrated in Figs. 1 to 6 inclusive has an arcuately shaped contact surface 92 at the inner and upper end of its slot or recess 58 for seating engagement upon the correspondingly shaped top surface of the keeper pin 17 when the door 16 is in closed position. In the embodiment of the invention illustrated in Figs. 7 and 8, however, the bifurcated door control member 14a is so shaped that two laterally spaced or separated contact or bearing surfaces 93 are provided at the inner and upper end of its slot or recess 58a for seating engagement upon the arcuately shaped top surface of the keeper pin 17a when the door 16a is in closed position. As shown in Fig. 8, such laterally spaced contact surfaces 93 are here disposed at substantially right angles to each other, (although the angular relationship of such contact surfaces obviously may be varied, as desired), with the result that when the door 16a is in its closed position, inward and outward movement of the bifurcated door control member 14a, and hence of said door, is effectively prevented. By the use of a door control member of the character illustrated in Figs. 7 and 8, therefore, as well as by the use of a door control member of the character illustrated in Figs. 1 to 6 inclusive,

door bumpers are not needed to insure for a door a single predetermined closed position, and the use of such door bumpers with the here illustrated embodiments of the present invention may be dispensed with. It is to be understood, of course, that the pivoted door control member 14 of the mechanism of Figs. 1 to 6 inclusive, and the pivoted door control members of the herein-after described mechanisms of Figs. 9 and 10, and of Figs. 13 and 14, may be provided, if desired, with opposed contact surfaces of the general character as those illustrated in Figs. 7 and 8, rather than with arcuately shaped contact surfaces, as here shown.

In the mechanism of Figs. 1 to 6 inclusive and in the mechanism of Figs. 7 and 8, the pivoted door control means (the bifurcated member 14 of Figs. 1 to 6 inclusive and the bifurcated member 14a of Figs. 7 and 8) have cooperative contact or engagement with movable take-up members (the slideable take-up member or wedge 60 of Figs. 1 to 6 inclusive and the pivoted take-up member 85 of Figs. 7 and 8) for rigidly or unyieldably holding a door against upward movement. If desired, however, the pivoted door control means of mechanism embodying the present invention may have cooperative contact or engagement, for such door-holding purposes, with a stationary or rigidly mounted holding member, and three embodiments of mechanism of such character are here illustrated, one such embodiment being illustrated in Figs. 9 and 10, another in Figs. 11 and 12, and still another in Figs. 13 and 14.

In the embodiment of the invention illustrated in Figs. 9 and 10, the pivotally mounted bifurcated door control member 14b has cooperative contact or engagement, for door-holding purposes, with a relatively flat plate-like holding member 95 which is rigidly associated in any suitable manner with that structure (either a door structure or the body frame structure therefor) with which is associated the keeper pin 17b. For example, said holding member 95 may be an integral part of the keeper pin base plate 26b, as here indicated, or it may be a separate member rigidly secured to such base plate in any suitable manner. As indicated in Figs. 9 and 10, the arcuately shaped top surface 96 of the door control member 14b is adapted for cooperative contact or engagement, for door holding purposes, with the correspondingly shaped bottom surface 97 of the rigidly mounted holding member 95, said holding member bottom surface and the top surface of the keeper pin 17b being spaced or separated sufficiently to permit said door control member 14b to be wedged therebetween upon the movement of said door control member to its single predetermined operative position, (or in other words, upon the movement to its single predetermined closed position of the door with which this mechanism is used). As here shown, the arcuately shaped top contact surface 96 of the door control member 14b is eccentrically related to the longitudinal axis of the stub shaft 21b about which such door control member swings, said top contact surface 96 being the arc of a circle of which the center is indicated at 98, (see Fig. 9) said center being located outwardly from the longitudinal axis of the stub shaft 21b.

As will be readily understood, upon the closing of the door with which is used the mechanism of Figs. 9 and 10, the door control member 14b will be swung from its predetermined operated posi-

tion, shown in Fig. 10, to its single predetermined operative position, shown in Fig. 9, the longitudinal axis of the stub shaft 21b having substantially horizontal movement. The arc center 98 of the door control member 14b, however, gradually rises during the movement of said member from its operated position to its operative position, with a corresponding rise, of course, of the top contact surface 96 of said member, 5 the path of movement of such top contact surface being indicated in Fig. 10 by the dot-dash line 99. Because of the rising character of the path of movement of the top contact surface 96 of the door control member 14b, there is no liability of such member moving beyond a single predetermined operative position, with the result 10 that a single predetermined closed position of the door with which such mechanism is used is insured. Moreover, as the angular relationship 15 of the cooperative contact surfaces 96, 97 of the door control member 14b and the rigidly mounted holding member 95 are of "locking" character, the rigid or unyieldable holding of the "latch" side of such door against upward movement relative to its surrounding frame likewise is insured, 20 all as will be readily understood.

In the embodiment of the invention illustrated in Figs. 11 and 12, the "latch" side of the door with which such mechanism is used is rigidly or 25 unyieldably held against upward movement by the cooperative contact or engagement of the generally horizontal bottom surface 102 of the rigidly mounted holding member 103 and the arcuately shaped top surface 104 of the pivotally mounted bifurcated door control member 14d, such top contact surface of said door control member being concentrically related to the stub shaft axis about which such member swings. In this embodiment of the invention, a take-up 30 member is associated with the keeper pin 17c, the take-up member here shown comprising a relatively short arm 106 and a depending extension 107, the lower end portion of said take-up member arm being pivotally mounted upon said keeper pin. When the door with which this mechanism is used is in open position, the take-up member of such mechanism occupies the position shown in Fig. 12, the depending extension 107 of said member being held against a stop pin 108 or the like by spring or other suitable 35 means 110.

Upon the movement to closed position of the door with which this mechanism is used, the arm 106 of the take-up member of such mechanism is engaged by the throw-out arm of the bifurcated door control member 14c, as indicated in Fig. 12, and during the movement of said door control member from its predetermined operated position to its single predetermined operative 40 position, said take-up member is swung from its Fig. 12 position to its Fig. 11 position, the latter position of said take-up member being its door holding position, as will be readily understood. When said take-up member is in its door holding 45 position, the arm 106 thereof is engaged by the bifurcated door control member 14c at two laterally spaced places, one on the outer side of the axis of the keeper pin 17c and the other on the inner side thereof, as clearly shown in Fig. 11.

Inasmuch as the cooperating outer contact surfaces of said door control member 14c and said take-up member arm 106 are of "locking" character, the seating engagement of said door control member upon said take-up member arm 50 effectively prevents, in a rigid or unyieldable man-

ner, any downward movement of the "latch" side of the door with which this mechanism is used. Moreover, as the door control member 14c is wedged between said take-up member arm 106 (said take-up member when in its door holding 5 position, Fig. 11, being immovable in an up and down direction) and the rigidly mounted holding member 103 when said door is in closed position, the "latch" side of such door is rigidly or unyieldably held against upward movement relative to its surrounding frame. With this mechanism, any wear which occurs will be readily taken up, as the pivoted door control member 14c, upon moving from its operated position to its operative position during door-closing movement, always moves the arm 106 of the take-up member of such mechanism to a position wherein such arm and said door control member contact or inter-engage for door-holding purposes, all as will be readily understood. 20

In the embodiment of the invention illustrated in Figs. 13 and 14, a take-up member 115 is pivotally mounted, by means of a pin 116, upon the upper end portion of the pivotally mounted bifurcated door control member 14d, for cooperative contact or engagement with the rigidly mounted holding member 117 in effecting rigid or unyieldable holding against upward movement of the "latch" side of the door with which this mechanism is used. As shown, the arcuately 30 shaped top surface 118 of said take-up member is located above the top surface of said door control member for door holding contact or engagement with the generally horizontal bottom surface 119 of the holding member 117, and inasmuch as such cooperative surfaces 118, 119 are of "locking" character, there is no liability of undesired lateral movement of said take-up member when such member is cooperatively related to said holding member for door holding purposes. Due to the eccentric relationship of the arcuately shaped top surface 118 of said take-up member relative to the axis of its pivot pin 116, the areas of contact of the surfaces 118, 119 are outwardly disposed, as clearly shown in Fig. 13, 45 relative to the center line of the pivot pin 116 and the stub shaft 21d about which swing, respectively, the take-up member 115 and the door control member 14d. As a result, no jamming of the parts is possible upon the opening of the door with which this mechanism is used. As with the pivoted take-up member 85 of the mechanism of Figs. 7 and 8, the take-up member 115 of this mechanism has provided therefor a stop pin 122 or the like and spring or other means 50 123 for normally urging said take-up member toward said stop pin or in a counter-clockwise direction, Figs. 13 and 14. Like the take-up spring 88 of the mechanism of Figs. 7 and 8, the take-up spring 123 of this mechanism automatically takes up or compensates for wear of the parts, etc.

From the foregoing description of several forms of mechanism embodying the present invention, it will be readily apparent that each of such mechanisms effects, in a particularly practical and efficient manner, the control of a hinged door and the rigid or unyieldable holding of the "latch" side of such door against movement in the general direction of its hinge axis (in an up 70 and down direction in the case of the doors here shown). If mechanism embodying the present invention is used with a door which swings about a horizontal axis, then such mechanism will effect the more or less rigid or unyieldable holding 75

of the "latch" side of such door against movement in a side to side or horizontal direction, the direction of the hinge axis of such door, all as will be readily understood.

5 Although each of the mechanisms here illustrated is adapted to rigidly or unyieldably hold the "latch" side of a door against movement in the general direction of its hinge axis, some movement of the "latch" side of a door in the 10 general direction of its hinge axis may be permitted, if desired, and it is quite obvious how each of the mechanisms here illustrated might be modified, in an exceedingly simple and inexpensive manner, to permit limited movement 15 of the "latch" side of each of the doors here shown in the general direction of its hinge axis. For example, in the mechanism illustrated in Figs. 1 to 6 inclusive, limited movement of the "latch" side of the door 16, in the general direction 20 of the hinge axis of such door, may be effected, if desired, by so mounting the slidable take-up member or wedge 60 and the keeper pin 17 that either or both thereof have limited movement in the general direction of the hinge axis 25 of such door. In an equally simple and obvious manner, each of the other mechanisms here illustrated may be modified to permit limited or more or less movement, in the general direction of its hinge axis, of the "latch" side of the door with 30 which such mechanism is used.

The present invention, therefore, covers and includes door holding and door control mechanism by means of which a hinge door is controlled and by means of which the "latch" side 35 of said door, when said door is in its closed position, is held against all movement, or is permitted to have limited movement only, in the general direction of the hinge axis of such door. In the appended claims, the term or expression "substantially immovable" is to be understood 40 and construed as covering or including not only total immovability but also, movability to a limited amount or degree.

It is not necessary, of course, that the keeper pins here shown be immovably or rigidly mounted, it being sufficient if such pins are immovable or substantially immovable, in the general directions of the hinge axes of the doors with which they are used, when such doors are in their 50 closed positions. Obviously, said keeper pins could be mounted for rotary movement about their longitudinal axes, as pointed out in my aforesaid Patent No. 2,094,413 for Door control mechanism (top of first column, page 4 of the 55 specification of such patent), or anti-friction sleeves could be rotatably mounted on such keeper pins, all as will be readily understood.

In the here illustrated embodiments of the present invention, the bifurcated door control members (14, 14a, etc.) not only cooperate with the keeper pins (11, 11a, etc.) for door control purposes but also, seat thereon for door holding purposes. It is to be understood, however, that such bifurcated door control members and such 60 keeper pins may be reversed or inverted as to their relative positions, so as to locate such keeper pins for seating engagement upon said bifurcated door control members, for door holding purposes, when the doors with which such mechanisms are 65 used are in their closed positions.

As heretofore referred to, mechanism embodying the present invention may provide a door latch control only, or a door throw-out control only, or a combined door latch and door throw-out control, the latter type of control having 70

been here shown for purposes of illustration and not of limitation. To enable any of the door holding and door control mechanisms here illustrated to provide a door throw-out control only, it is merely necessary to remove from the pivoted door control member of such mechanism the latch arm thereof, which may be easily and quickly accomplished, and to provide for the door with which such mechanism is used any suitable latch means or the like for releasably retaining 10 said door in closed position. The door control provided by such mechanism will then be a door-throw-out control only. To enable any of the door holding and door control mechanisms here illustrated to provide a door latch control only, 15 it is merely necessary to substitute in such mechanism for the spring or power means 32 (shown only in connection with the embodiment of the invention illustrated in Figs. 1 to 6 inclusive) a spring or the like with insufficient force to effect 20 door throw-out movement. The sole function of such a "light" spring or the like will then merely be the automatic maintenance of the latch and "crank" arms of such mechanism in operated 25 position when the door with which such mechanism is used is in open position, all as will be readily understood.

Further objects and advantages of the present invention will be obvious to those skilled in the art to which it relates.

What I claim is:

1. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, and door holding means adapted 45 to be so associated with the structure with which such "immovable" door control means is associated that such door holding means is substantially immovable in the general direction of the hinge axis of the door structure when said door structure is in closed position, and door holding means adapted 50 to be so associated with the structure with which such "immovable" door control means is associated that such door holding means is substantially immovable in the general direction of the hinge axis of the door structure when said door structure is in closed position, with the result 55 that when said door structure is in closed position its aforesaid part is substantially immovable in the general direction of the hinge axis of said door structure, said pivoted door control means having two laterally opposed contact surfaces at 60 substantially right angles to each other for wedging contact with said "immovable" door control means when the door structure is in closed position, with the result that the aforesaid part of said door structure is substantially immovable in 65 a door opening and door closing direction when said door structure is in closed position.

2. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being 70

adapted to be so associated with a part of the other of said structures that such last mentioned door control means is substantially immovable in the general direction of the hinge axis of the 5 door structure when said door structure is in closed position, one of said two door control means having spaced arm portions which are disposed on opposite sides of the other of said door control means when the door structure is 10 in closed position, and door holding means adapted to be so associated with the structure part with which such "immovable" door control means is associated that such door holding means is substantially immovable in the general direction 15 of the hinge axis of the door structure when said door structure is in closed position, said door holding means and said "immovable" door control means being spaced apart and said pivoted door control means being wedged therebetween 20 25 when said door structure is in closed position, with the result that when said door structure is in closed position its aforesaid part is substantially immovable in the general direction of the hinge axis of said door structure.

3. In combination with a hinged door structure and a door frame structure therefor, door holding and door latch control mechanism comprising two cooperatively related door latch control means for the latch control of said door structure, one of such door control means being adapted to be pivotally associated with a part of one of said structures and the other of such door control means being adapted to be so associated with a part of the other of said structures 30 that such last mentioned door control means is substantially immovable in the general direction of the hinge axis of the door structure when said door structure is in closed position, the cooperative relation of said two door control means being of such character that the only relative movement thereof when such two means are in cooperative engagement during opening and closing movement of said door structure is the pivotal movement of said pivoted door control means, and door holding means adapted to be so 35 associated with the structure part with which such "immovable" door control means is associated that such door holding means is substantially immovable in the general direction of the hinge axis of the door structure when said door structure is in closed position, said door holding means and said "immovable" door control means being spaced apart and said pivoted door control means being wedged therebetween 40 45 when said door structure is in closed position, the cooperative wedging engagement of two of the three aforesaid means being effected through a movable take-up member with which one of said two means is provided, said take-up member being substantially immovable in the general direction of the hinge axis of the door structure when said door structure is in closed position, with the result that 50 when said door structure is in closed position its aforesaid part is substantially immovable in the general direction of the hinge axis of said door structure.

4. In combination with a hinged door structure and a door frame structure therefor, door holding and door latch and throw-out control mechanism comprising two cooperatively related door latch and door throw-out control means for the latch and throw-out control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said 55 60 65 70 75

door structure is in closed position, said pivoted door control means having an operative position when the door structure is closed and an operated position when the door structure is open and such pivoted door control means having a normal tendency to swing toward its operated position, and door holding means adapted to be so associated with the structure part with which such "immovable" door control means is associated that such door holding means is substantially immovable in the general direction of the hinge axis of the door structure when said door structure is in closed position, said door holding means and said "immovable" door control means being spaced apart to receive said pivoted door control means in wedging relation as the door structure approaches closed position and while said pivoted door control means has its aforesaid normal tendency and said pivoted door control means being wedged therebetween when said door structure is in closed position, with the result that when said door structure is in closed position its aforesaid part is substantially immovable in the general direction of the hinge axis of said door structure. 25

5. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, one of said two door control means having spaced arm portions which are disposed on opposite sides of the other of said door control means when the door structure is in closed position, and door holding means adapted to be so associated with the structure part with which such "immovable" door control means is associated as to be substantially immovable in the general direction of the hinge axis of the door structure when said door structure is in closed position, said door holding means and said "immovable" door control means being spaced apart and said pivoted door control means being wedged therebetween when said door structure is in closed position, the cooperative wedging engagement of two of the three aforesaid means being effected through a movable take-up member with which one of said two means is provided, said take-up member being substantially immovable in the general direction of the hinge axis of the door structure when said door structure is in closed position, with the result that when said door structure is in closed position its aforesaid part is substantially immovable in the general direction of the hinge axis of said door structure. 40 45 50 55 60 65 70 75

6. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door control means is substantially immovable in 75

the general direction of the hinge axis of the door structure when said door structure is in closed position, and door holding means adapted to be so associated with the structure part with which such "immovable" door control means is associated as to be substantially immovable in the general direction of the hinge axis of the door structure when said door structure is in closed position, said door holding means and said "immovable" door control means being spaced apart and said pivoted door control means being wedged therebetween when said door structure is in closed position, the cooperative wedging engagement of two of the three aforesaid means being effected through a slidable take-up member with which one of said two means is provided, said take-up member being substantially immovable in the general direction of the hinge axis of the door structure when said door structure is in closed position, with the result that when said door structure is in closed position its aforesaid part is substantially immovable in the general direction of the hinge axis of said door structure.

7. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, one of said two door control means having spaced arm portions which are disposed on opposite sides of the other of said door control means when the door structure is in closed position, and door holding means adapted to be so associated with the structure part with which such "immovable" door control means is associated as to be substantially immovable in the general direction of the hinge axis of the door structure when said door structure is in closed position, said door holding means and said "immovable" door control means being spaced apart and said pivoted door control means being wedged therebetween when said door structure is in closed position, the cooperative wedging engagement of two of the three aforesaid means being effected through a pivoted take-up member with which one of said two means is provided, said take-up member being substantially immovable in the general direction of the hinge axis of the door structure when said door structure is in closed position, with the result that when said door structure is in closed position its aforesaid part is substantially immovable in the general direction of the hinge axis of said door structure.

8. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door

structure when said door structure is in closed position, and door holding means adapted to be so associated with the structure part with which such "immovable" door control means is associated as to be substantially immovable in the general direction of the hinge axis of the door structure when said door structure is in closed position, said door holding means and said "immovable" door control means being spaced apart and said pivoted door control means being wedged therebetween when said door structure is in closed position, the cooperative wedging engagement of two of the three aforesaid means being effected through a movable take-up wedge with which one of said two means is provided, said take-up wedge being substantially immovable in the general direction of the hinge axis of the door structure when said door structure is in closed position, with the result that when said door structure is in closed position its aforesaid part is substantially immovable in the general direction of the hinge axis of said door structure.

9. In combination with a hinged door structure and a door frame structure therefor, door holding and door latch control mechanism comprising two cooperatively related door latch control means for the latch control of said door structure, one of such door control means being adapted to be pivotally associated with a part of one of said structures and the other of such door control means being adapted to be associated with a part of the other of said structures, said last mentioned door control means having pivotally associated therewith a take-up member so constructed and arranged as to be substantially immovable in the general direction of the hinge axis of the door structure when said door structure is in closed position, said pivoted door control means having cooperative engagement with said take-up member for door latching purposes, and door holding means adapted to be so associated with the structure part with which is associated the door control means having such take-up member that such door holding means is substantially immovable in the general direction of the hinge axis of the door structure when said door structure is in closed position, said door holding means and the take-up member of said last mentioned door control means being spaced apart and said pivoted door control means being wedged therebetween when said door structure is in closed position, with the result that when said door structure is in closed position its aforesaid part is substantially immovable in the general direction of the hinge axis of said door structure.

10. In combination with a hinged door structure and a door frame structure therefor, door holding and door control mechanism comprising two cooperatively related door control means for the control of said door structure, one of such door control means being of bifurcated form and of rigid character and being adapted to be pivotally associated with a part of one of said structures and the other of such door control means being of stud-like form and adapted to be so associated with a part of the other of said structures that such last mentioned door control means is immovable in the general direction of the hinge axis of the door structure when said door structure is in closed position, the bifurcated door control means being in straddling relation relative to said stud-like door control means when the door structure is in closed position, and door holding means adapted to be so associated with the structure part with which such immovable

door control means is associated that such door holding means is immovable in the general direction of the hinge axis of the door structure when said door structure is in closed position, said door holding means and said immovable door control means being spaced apart and said pivoted door control means being wedged therebetween when said door structure is in closed position, with the result that when said door structure is in closed position its aforesaid part is immovable in the general direction of the hinge axis of said door structure.

11. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, and door holding means adapted to be so associated with the structure part with which such "immovable" door control means is associated that such door holding means is substantially immovable in the general direction of the hinge axis of the door structure when said door structure is in closed position, said door holding means adapted to be so associated with the structure part with which such "immovable" door control means is associated that such door holding means is substantially immovable in the general direction of the hinge axis of the door structure when said door structure is in closed position, said door holding means and said "immovable" door control means being spaced apart and said pivoted door control means being wedged therebetween when said door structure is in closed position, with the result that when said door structure is in closed position its aforesaid part is substantially immovable in the general direction of the hinge axis of said door structure, the effective cooperative contact surfaces of said pivoted door control means and said "immovable" door control means for door holding and door latching purposes and the effective cooperative contact surfaces of said pivoted door control means and said door holding means for door holding purposes being in substantial alignment in the general direction of the hinge axis of the door structure when said door structure is in closed position.

12. In combination with a hinged door structure and a door frame structure therefor, door holding and door control mechanism comprising two cooperatively related door control means for the control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, one of said two door control means having spaced arm portions which are disposed on opposite sides of the other of said door control means when the door structure is in closed position, and door holding means adapted to be associated with the structure part with which such "immovable" door control means is associated and having a pivoted take-up member so constructed and arranged as to be substantially immovable in the general direction of the hinge axis of the door structure when said door structure is in closed position, said take-up member being above and spaced from said "immovable" door control means and said pivoted door control means being wedged therebetween when the door

structure is in closed position, with the result that when said door structure is in closed position its aforesaid part is substantially immovable in the general direction of the hinge axis of said door structure.

13. In combination with a hinged door structure and a door frame structure therefor, door holding and door latch control mechanism comprising two cooperatively related door latch control means for the latch control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, and door holding means adapted to be so associated with the structure part with which such "immovable" door control means is associated that such door holding means is substantially immovable in the general direction of the hinge axis of the door structure when said door structure is in closed position, said door holding means and said "immovable" door control means being spaced apart and said pivoted door control means being wedged therebetween when said door structure is in closed position, with the result that when said door structure is in closed position its aforesaid part is substantially immovable in the general direction of the hinge axis of said door structure, the effective cooperative contact surfaces of said pivoted door control means and said "immovable" door control means for door holding and door latching purposes and the effective cooperative contact surfaces of said pivoted door control means and said door holding means for door holding purposes being in substantial alignment in the general direction of the hinge axis of the door structure when said door structure is in closed position.

14. In combination with a hinged door structure and a door frame structure therefor, door holding and door latch control mechanism comprising two cooperatively related door latch control means for the latch control of said door structure, one of such door control means being adapted to be pivotally associated with a part of one of said structures and the other of such door control means being adapted to be so associated with a part of the other of said structures that such last mentioned door control means is substantially immovable in the general direction of the hinge axis of the door structure when said door structure is in closed position, and door holding means adapted to be so associated with the structure part with which such "immovable" door control means is associated that such door holding means is substantially immovable in the general direction of the hinge axis of the door structure when said door structure is in closed position, said door holding means and said "immovable" door control means being spaced apart and said pivoted door control means being wedged therebetween when said door structure is in closed position, the cooperative wedging engagement of two of the three aforesaid means being effected through a movable take-up member with which one of said two means is provided, said take-up member being substantially immovable in the general direction of the hinge axis of the door structure when said door structure is in closed position, with the result that when said

door structure is in closed position its aforesaid part is substantially immovable in the general direction of the hinge axis of said door structure, the effective cooperative contact surfaces of said 5 pivoted door control means and said "immovable" door control means for door holding and door latching purposes and the effective cooperative

contact surfaces of said pivoted door control means and said door holding means for door holding purposes being in substantial alignment in the general direction of the hinge axis of the door structure when said door structure is in 5 closed position.

RUDOLPH I. SCHONITZER.
